Atty.

UNITED STATES PATENT OFFICE

THEODOR GREIS, OF KREFELD, GERMANY

ROLL FOR CALENDERING MACHINES

Application filed March 15, 1928, Serial No. 282,016, and in Germany November 24, 1926.

My invention refers to calendering machines and more especially to the elastic rolls forming part of such machines. It is an object of my invention to provide such rolls with a covering which renders them more efficient than those hitherto in use.

The covering of elastic rolls for calendering machines as hitherto designed is formed by separate discs made of paper, fabric or 10 wadding, these discs being forced upon the core of the roll by pressure.

In the operation of such rolls it has been found that it is not possible to impart to them uniform hardness and elasticity on the entire 15 circumference and in consequence of this deficiency the furrowed fabrics or glazed softened paper after being treated on the calendering machine showed the formation of strips or shadows. Moreover the life of such 20 rolls is comparatively short.

In order to avoid this, I form the covering for such rolls from a spiral band or ribbon standing on edge and in which the weft is arranged in staggered relation, the weft 25 forming the operative part of the covering.

In the drawing affixed to this specification and forming part thereof part of the cross-section of a calendering roll embodying my invention is illustrated diagrammatically by 30 way of example.

Fig. 1 is an end elevation of the roll, and Fig. 2 is a perspective illustration showing the band or ribbon partly unwound from its core.

35 In the drawings, *a* is the core and *b* is the covering. In this covering *h* is the warp of the spiral or serpentine ribbon or band, and *i* is the weft which is shown as differing in length radially, the single weft 40 threads being arranged in staggered relation. The distance *c* shows the thickness of the layer which is gradually worn down, while the distance *d* shows that part of the roll which remains over. The part *c* is formed 45 almost entirely of weft threads *i* and contains

only as many warp threads as are required in order to hold the weft together. In contradistinction thereto in the part *d*, the warp *h* and the staggered weft threads *i* are distributed as required for a uniform thickness of the fabric. All fibres constituting the weft threads extend spirally wound threads 50 radially to the axis of the core.

The surface of a roll composed as hereinbefore described is of uniform hardness on 55 its entire circumference and, owing to all the fibres having the same direction, also uniform elasticity, which is increased by the fact that the fibres stand on edge. The covering is less sensitive to knots and creases, as all the fibres 60 have the tendency of rising directly after having been compressed. The life of a roll constituted in accordance with this invention is also lengthened in consequence of the radial arrangement of the fibres. The pressure 65 exerted upon the roll by the counter roll enters the covering down to a certain depth. When in operation the covering is permanently moving down to this depth. The spirally wound fibres are more resistive against 70 this constant movement.

From an economical point of view the rolls manufactured according to the present invention offer the advantage that the warp threads *h* in the inner portion *d* may be made 75 of an inferior material as compared with the warp threads in the outer portion *c*.

Various changes may be made in the details disclosed in the foregoing specification without departing from the invention or sacrificing the advantages thereof.

I claim:—

1. A roll for calendering machines comprising a core and a band or ribbon wound about said core standing on edge, the weft 85 threads in said band or ribbon being arranged in staggered relation.

2. A roll for calendering machines comprising a core and a band or ribbon wound about said core standing on edge, the weft

threads in said band or ribbon differing in length.

3. A roll for calendering machines comprising a core and a band or ribbon wound about said core standing on edge, the weft 5 threads in said band or ribbon extending to various depths in radial direction.

4. A roll for calendering machines comprising a core and a band or ribbon wound about said core standing on edge, the number 10 of the weft threads in the outer portion of said roll being in excess of their number in the inner portion.

In testimony whereof I affix my signature.

THEODOR GREIS.
